United States Patent Office.

JOHN J. KENNA, OF SAN FRANCISCO, CALIFORNIA.

Letters Patent No, 91,138, dated June 8, 1869.

IMPROVEMENT IN MACHINES FOR POLISHING SHIRT-BOSOMS.

The Schedule referred to in these Letters Patent and making part of the same.

To all whom it may concern:

Be it known that I, JOHN J. KENNA, of the city and county of San Francisco, and State of California, have invented a new and useful Improvement on the Rolls of Machines for Polishing Shirt-Bosoms; and I do hereby declare that the following is a full, clear, and exact description of the construction and operation of the same, reference being had to the annexed drawings, in which—

Figure 1 is an edge view, and

Figure 2 is a side view.

To enable others skilled in the art to make and use my invention, I will proceed to describe its construction and operation.

The roll I construct in the usual manner. But in order that the neck-binding of a bosom may not be

folded down upon itself, and wrinkled by the polishing-iron passing over it during the revolution of the roll, I make a recess on one side of the roll, of a shape conforming to that of the neck-binding, and of sufficient depth to allow the binding to drop into it and the polishing to pass freely over it, thereby more easily and effectively polishing the bosom, without wrinkling the binding.

What I claim as my invention, and desire to secure by Letters Patent, is—

The roll A, provided with the recess B, substantially as and for the purpose set forth.

JNO. J. KENNA.
